Primary Examiner — T. Chase Nelson*Assistant Examiner* — Michelle E Wilson*(74) Attorney, Agent, or Firm* — Shay Glenn LLP(57) **CLAIM**

We claim the ornamental design for a iontophoretic drug delivery device, as shown.

DESCRIPTION

FIG. 1 is a top elevational view of a iontophoretic drug delivery device.

FIG. 2 is a bottom elevational view of the iontophoretic drug delivery device.

FIG. 3 is a left side elevational view of the iontophoretic drug delivery device.

FIG. 4 is a right side elevational view of the iontophoretic drug delivery device.

FIG. 5 is a front elevational view of the iontophoretic drug delivery device.

FIG. 6 is a back elevational view of the iontophoretic drug delivery device.

FIG. 7 is a top left front perspective view of the iontophoretic drug delivery device.

FIG. 8 is a top right back perspective view of the iontophoretic drug delivery device; and,

FIG. 9 is a bottom right back perspective view of the iontophoretic drug delivery device.
